UNITED STATES PATENT OFFICE.

THOMAS H. STAFFORD, OF FRANKLIN, NEW HAMPSHIRE.

GAS-MANTLE LAMP.

1,340,424.

Specification of Letters Patent. Patented May 18, 1920.

Application filed March 20, 1919. Serial No. 283,755.

To all whom it may concern:

Be it known that I, THOMAS H. STAFFORD, a citizen of the United States, resident of Franklin, in the county of Merrimack and State of New Hampshire, have invented certain new and useful Improvements in Gas-Mantle Lamps, of which the following is a specification.

This invention relates to portable lamps and has particular reference to that type of lamps which generate gas from a liquid fuel such as kerosene and employ mantles which are heated to incandescence by the burning gas. In a heretofore known lamp of this type the fuel is contained in a reservoir or font and is under pressure which forces it up through a filtering tube and a generator located to receive such heat from the incandescent mantle or mantles as to gasify the liquid fuel. The gas then passes through a somewhat tortuous passage to which air is admitted and mixed with the gas, and the mixture then issues from one or more nipples having mantles of a well known type attached thereto.

Lamps of this type require that occasional access be had to the generator to keep the passage therethrough free from obstructions. As the generator is necessarily very close to the mantle or mantles, and as the latter are (after having been first "burned off") very fragile, the temporary displacement of the generator for cleaning purposes frequently breaks the mantle. One of the objects of the present invention is to provide structures of lamps of this type which will permit of moving the mantles and generators apart and holding them separated so as to avoid any risk of fracturing a mantle when the generator is disconnected to be cleaned.

Another difficulty has been found to exist in regard to the filter tubes. Such tube usually has a filling or wick of asbestos and after some use the wick becomes so filled with carbon that sufficient fuel can not pass through. The tubes must then be replaced by a new wick-filled tube because the carbon causes such adhesion to the inner wall of the tube that the wick can not be pulled out and replaced by a new piece of wicking. A most important feature of my invention resides in the provision of means whereby the wick in the tube can be readily removed and

the inside of the tube cleared at the same time, so that a new or fresh wick can be placed in the tube.

Other objects and advantages will be referred to hereinafter and the novel features of my invention will be pointed out in the claims.

Of the accompanying drawings:

Figure 1 is a side elevation, partly in section, of so much of one of my complete lamps as is necessary to an understanding of the invention, the oil reservoir or font and shade being unnecessary to illustrate.

Fig. 2 is a side elevation of the gasifier or generator on a larger scale.

Fig. 3 represents a section on line 3—3 of Fig. 2.

Fig. 4 is a sectional elevation of the feed tube and its contained filtering wick.

Fig. 5 is a view similar to Fig. 4 illustrating the operation of removing a carbonized wick from the tube.

Fig. 6 is a sectional detail of one of the mantle-supporting nipples.

Fig. 7 is a view similar to a portion of Fig. 1, illustrating the rising mixing head as having a ring-shaped or circular mantle instead of two cup-shaped mantles.

Fig. 8 represents a transverse vertical section through the lower part of Fig. 7.

Mounted on an oil supply tube 12 rising from a suitable base font not shown, is a ring or small casting 13 which supports a pair of frame rods 14 the upper ends of which are formed or provided with ears 15 which are vertically apertured to provide bearings for two sliding rods 16 which are carried by the gas-mixing and mantle-carrying heads 17. The rods 16 pass through upper ears 18 of the head 17 and are tapped into lower ears 19 of said head. By any suitable means, such as by so forming the rods 16 that if not fitted in place they would be slightly curved, I provide for such friction between the rods and their bearings in the frame ears 15 that the head 17 when raised to the elevated position indicated by dotted lines in Fig. 1 will remain in that position while the generator is being cleaned and replaced, after which the head can be slid down to operative position.

A shade ring 20 is secured in any suitable manner to the rods 14 or the ears 15. As any kind of shade may be employed if de-

sired, supported by the ring 20 by any preferred connections, it is unnecessary to illustrate more than the ring 20.

The mixing and mantle-carrying head 17 which I term the "rising head" for reasons hereinafter made clear, is formed interiorly to provide a central passage communicating at its upper end with two side passages as indicated by dotted lines in Fig. 1. At the lower end of each side passage is a nipple 21 (Figs. 1 and 6) which is formed to have attached to it in the usual manner a mantle 22 of the customary or any preferred make. When the rising head is lifted 15 the mantles of course rise with it.

An air intake tube enters the side of the central passage of the head, near its lower end, as at 23, and fitting a hole in the bottom of said passage as a cork fits a bottle-neck is 20 the upper end or tip 24 of the generator 25 having a central passage 26 (Figs. 2 and 3). The generator as a whole stands vertically and is wide and flat, having wings the sides of which are preferably concaved as at 27 25 to better gather in or retain the heat radiated from the mantles to the opposite sides of the generator so that oil passing into the tube 26 from below will be the more quickly and efficiently heated and converted into gas 30 which then passes through the small aperture in the tip 24 and into the head 17 where it is mixed with air entering at 23 and passes to the mantles on opposite sides of the generator when the parts are in operative relative positions as indicated by the full lines 35 in Fig. 1.

Connected to the lower end of the generator, preferably by screw threads, is the tube 28 (Figs. 1, 4 and 5) for containing the 40 filtering material which is usually asbestos braid. The lower end of the tube is knurled as at 29, or has a knurled end piece secured to it, and has a threaded nipple 30 to removably engage the upper end of the supply tube 12.

Snugly fitting the interior of the tube 28 is a closely coiled wire 31 which closely wraps the wick material 32 (Fig. 4). The object of the wire is to facilitate removal of 50 a piece of wicking which has become clogged owing to the heat resulting from proximity to the generator and mantles. It serves as a wick extractor and to clear the inside of the tube for the reception of a fresh wire-wrapped wick. When the wick fails to permit proper flow of oil, the tube is 55 separated from its connected parts and then the exposed end of the coil 31 is grasped and pulled up as indicated in Fig. 5. This 60 elongation or lengthening of the coil breaks up any lining of carbon or other objectionable material which may cause adhesion to the inside of the tube, and the coils as they are drawn out scrape the inside of the tube. 65 The wire 31 is so closely coiled that there

are no spaces between the coils and therefore there is no opportunity for the accumulation of such quantities of carbon as would fail to break when the wire is elongated as shown in Fig. 5. As the last of the 70 coil leaves the tube the wick usually goes with it. If any particles of carbon remain in the tube they can be easily knocked out or blown out. Then a fresh wick inclosed by a coil is inserted in the tube and operative connections re-established. This removable coiled lining of the tube may be of wire which is either round or flattened or angular in cross section.

Prior to attempting to gain access to the 80 generator to prick out the aperture in its tip 24, or to the filter wick in the tube 28, the head 17 is raised and left elevated (see dotted lines in Fig. 1). This also raises the mantles and supports them high enough to 85 enable the tip 24 to be pricked out if that is all that is required, without danger of fracturing the fragile mantles. Also while the head and mantles remain raised the generator and wick tube can be unscrewed and removed for examination or repairs, without 90 damage to the mantles. The plug fit of the generator tip 24 in the bottom hole of the head enables the separation to be readily effected, and when the generator and wick 95 tube are back in place a simple sliding down or lowering of the head until its bottom hole fits snugly onto tip 24 restores the parts to condition for use.

While I have so far described my invention as including two mantles 22, it is obvious that one of them and one of the nipples 21 might be omitted. I prefer, however, for some purposes, to employ a single mantle which entirely surrounds the generator when said parts are in relative positions for use. Such a mantle is circular or ring-shaped as illustrated in Figs. 7 and 8 in which all parts having the same reference numerals as in the other figures are or 100 may be the same as in said other figures. In said Figs. 7 and 8, the outer or side passages of the rising head 17 deliver the mixed gas and air into a circular chamber 115 36 the inner wall of which has an annular groove 37 and the outer wall of which has an external groove 38. The circular bottom of the chamber has ports 39 for the passage of the inflammable mixture into the ring-shaped mantle 40. This mantle may be secured in place by any suitable means such as an expansible split ring 41 clamping its inner margin in the groove 37 and a thread or cord binding its outer margin in the groove 38. This form of mantle gives the 120 greatest possible results in illumination, owing to its having inner as well as outer concentric walls, and a bottom.

It will be readily understood that the feature of the rising head carrying the mantle 130

with it has a special function when the mantle is circular and surrounds the generator when the lamp is in use, and it will also be appreciated that with the generator so enclosed it is subjected to a most effective heating from the mantle. If no provisions were made for displacing one relatively to the other and holding them so displaced, it would be almost if not quite impossible to do the usual things required to keep the lamp in operative condition without fracturing the mantle.

Having now described my invention, I claim:

- 15 1. A gas-burning lamp having a ring-shaped mantle holder provided with gas ports, a mantle having inner and outer margins secured to the inner and outer portions, respectively, of the holder, a generator extending within the mantle, and means for temporarily supporting the generator and mantle in relatively displaced positions.
- 20 2. A gas-burning lamp having a ring-shaped mantle, a generator surrounded by said mantle, means for conducting gas from the generator to the interior of the ring-shaped mantle, and means for temporarily holding the mantle in raised position to expose the generator.
- 25 3. In a lamp of the character described a generator and a mantle-supporting head having coupling connections to enable the generator to supply gas to said head, said

head having means for supporting it uncoupled and in raised position at a distance 35 from the generator to hold a mantle carried by the head clear of the generator.

4. In a lamp of the character described, a vertical generator having heat transmitting extensions, and means for directly heating 40 both sides of the generator.

5. In a lamp of the character described, a vertical generator having a central passage and oppositely extending heat transmitting wings, and means for directly heating both 45 sides of the generator.

6. In a lamp of the character described, a short straight oil feeding tube having a combined wick and wick extractor removably contained therein, said extractor consisting of wire coiled around the wick and having its upper end exposed to enable it to be elongated. 50

7. As an article of manufacture, for a lamp of the character described, a coil of 55 wire and fibrous material contained therein, the coils of the wire being in contact with each other to form a continuous tube.

8. In a lamp of the character described, a generator having vertically extending 60 wings, said wings having concave external surfaces, and means for directly heating said concave surfaces.

In testimony whereof I have affixed my signature.

THOMAS H. STAFFORD.
